UNITED STATES PATENT OFFICE

155,787

DESIGN FOR A HEAD CASTING FOR BICYCLE

Jack Dougherty, Chicago, Ill., assignor to Monark
Silver King, Inc., Chicago, Ill., a corporation of
Delaware

Application February 21, 1949, Serial No. 999

Term of patent 14 years

(Cl. D90—9)

To all whom it may concern:

Be it known that I, Jack Dougherty, a citizen of the United States, residing at Chicago, county of Cook, and State of Illinois, have invented a new, original, and ornamental Design for a Head Casting for Bicycle, of which the following is a specification, reference being had to the accompanying drawing forming a part thereof, in which:

Figure 1 is a perspective view of a head casting for bicycle, showing my new design; Fig. 2, a view similar to Fig. 1 but showing the opposite side of the casting; Fig. 3, a top plan view with the casting inclined rearwardly; Fig. 4, a top plan view showing the casting with its front side moved to a vertical position; Fig. 5, a front view in elevation; and Fig. 6, a side view in elevation.

I claim:

The ornamental design for a head casting for bicycle, as shown.

JACK DOUGHERTY.
